BLENDER JAR OR SIMILAR ARTICLE

Robert J. Emmons, 53 Country Lane,
Collinsville, Conn. 06022

Filed Aug. 20, 1973, Ser. No. 389,670

Term of patent 14 years

Int. Cl. D7—04

U.S. Cl. D7—154

FIG. 1

FIG. 2

FIG. 3

FIG. 4

FIG. 5

FIG. 1 is a top perspective view of a blender jar or similar article showing my new design, the broken line representation of a cover being for illustrative purposes only;

FIG. 2 is a side elevational view thereof;

FIG. 3 is a side elevational view thereof taken at a 45° angle to the plane of the view in FIG. 2, all sides being the same;

FIG. 4 is a top plan view thereof; and

FIG. 5 is a bottom plan view thereof.

I claim:

The ornamental design for a blender jar or similar article, as shown and described.
